UNITED STATES PATENT OFFICE.

FRANK ERNEST BARKER, OF BIRMINGHAM, ENGLAND, ASSIGNOR TO BARKER BROS. SIL-
VERSITHS LTD., OF BIRMINGHAM, ENGLAND, A COMPANY.

DESIGN FOR A TRAY OR RECEPTACLE.

No. 39,228.

Specification for Design.

Patented March 31, 1908.

Application filed December 23, 1907. Serial No. 407,851. Term of patent 7 years.

To all whom it may concern:

Be it known that I, FRANK ERNEST BARKER, a subject of the King of Great Britain, and residing at Birmingham, England, have invented a new, original, and ornamental Design for Trays or Receptacles, of which the following is a specification, reference being had to the accompanying drawings, forming part hereof.

The drawing represents a plan view, from above, of a tray, showing my new design.

I claim:

The ornamental design for a tray or receptacle, as shown.

FRANK ERNEST BARKER.
